CLASP FOR ARTICLES OF JEWELRY
AND THE LIKE

Oswin C. Woodward, Plainville, Mass., assignor to Harold E. Sweet, Attleboro, Mass., doing business as R. F. Simmons Company, Attleboro, Mass.

Application September 23, 1933, Serial No. 690,662

6 Claims. (Cl. 24—230)

This invention relates to an improved clasp for connecting the ends of cords, straps, linkages and other flexible bands used in watch bracelets, lavalieres, necklaces and like articles of utility or adornment.

One object of the invention is to provide a compact ornamental clasp having means for securely holding the ends of silk cords, leather or mesh straps, linked chains and other flexible bands.

Another object of the invention is to provide a clasp of the type indicated which comprises only two simple parts designed for economical manufacture from sheet-metal stampings and adapted for assembling without the use of pins, rivets, screws or the like.

Another object of the invention is to provide a clasp of the type indicated having clamping or gripping means for the cords, straps or linkages which are automatically rendered operative by simply assembling the two parts of the device one with the other.

Another object of the invention is to provide a clasp of the type indicated wherein the clamping or gripping action for holding the ends of the cords, straps or linkages is effected by sliding one part within the other whereby to render its manual operation more readily and expeditiously accomplished.

Another object of the invention is to provide a clasp of the type indicated which may be conveniently operated to release the ends of the cord, strap, linkage or other band when it is required to renew the latter or to adjust them in length.

Further objects of the improvement are set forth in the following specification which describes several preferred forms of the construction of the clasp, by way of example, as illustrated in the accompanying drawing. In the drawing:

Fig. 1 is a view of a conventional type of cord bracelet for wrist-watches showing the present improved clasp as applied to use therewith for attaching the ends of the cords to a central connector;

Fig. 2 is an enlarged side view of the two parts of the clasp shown in extended relationship with a portion of the outer enclosing member broken away;

Fig. 3 is a longitudinal sectional view of the same taken through the outer clasp member and showing the inner gripping member as released to be withdrawn therefrom;

Fig. 4 is a similar sectional view showing the inner member of the clasp enclosed and locked within the outer member;

Fig. 5 is a bottom plan view of the clasp;

Fig. 6 is an end view of this form of the device;

Fig. 7 is a transverse sectional view of the same taken on line 7—7 of Fig. 4;

Fig. 8 is a similar sectional view showing a modified form of construction of the inner clamping member of the clasp;

Fig. 9 is a similar sectional view showing a modified form of construction of both parts of the clasp;

Fig. 10 is a perspective view of the outer enclosing member of the clasp shown as being partially formed before assembling it with the inner member and illustrating a modification in its form of construction;

Fig. 11 is a perspective view of the inner clamping member of the clasp;

Fig. 12 is a longitudinal sectional view similar to Fig. 4 showing the present improved clasp adapted for use with a fabric or leather strap or band;

Fig. 13 is a similar longitudinal sectional view showing an adaptation of the strap for use in connecting the end of a chain or linkage.

Fig. 14 is a perspective view showing the clasp adapted for use with a mesh bracelet or the like; and

Fig. 15 is a perspective view showing a modification in the form of construction of the clamping member.

In accordance with a prevailing mode, wrist-watch bracelets, lavalieres, necklaces and other articles of utility and adornment are constituted by silk, leather or other ornamental cords embodied in their make-up. For example, in Fig. 1 there is represented a watch bracelet embodying silk cords C doubled on themselves to form loops at the ends for fastening them to the connectors 2 which clasp around the bails of the wrist-watch.

This type of ornamental cord bracelet is usually provided with a central clasp for connecting and disconnecting the ends of the opposite cord lengths in placing the bracelet on and removing it from the wrist. As herein illustrated, the means for joining the ends of the cords at the center of the bracelet may comprise a connector 4 having hinged parts adapted to engage through

opposite links 5 to couple them together. The links 5 or other parts of the connector are joined to the cords C by means of the present improved clasp as shown in detail in the enlarged views of the drawing.

The present improved clasp comprises, in general, a hollow or tubular box-like outer member 3 having a hook or loop 9 at one end for coupling

it to one of the links 5 or in any other part of the bracelet or the like; and a clamping member 10 which is slideable within the outer member 8 for clasping engagement therewith. The outer member 8 may be made from tubular stock of rectangular or other suitable cross-section; or it may be stamped out and formed from sheet-metal with a top 11, depending sides 12 and in-turned flanges 13 at the bottom between which is an opening.

At one end of the member 8 the bottom flanges 13 are extended beyond the ends of the sides 12 and bent upwardly at right-angles to form detent-fingers or abutments 15, see Figs. 2, 3 and 10. Above the detent-fingers 15 and sides 12 of the member 8 are formed with projections or lugs 16 which are bent inwardly across the open end of the member 8, as shown in Fig. 6 of the drawing, to adapt them to serve as stops for a purpose as later explained.

The inner member 10 is constructed in the form of a U-shaped clamp having opposite arms or jaws 18 and 19 between which the end of the cord, strap, band or linkage is held; the clamping member being arranged to telescope or slide within the member 8 in a manner as hereinafter more fully explained. The member 10 may be formed from a strip of sheet-metal bent into a loop 20 extended in the two arms 18 and 19, one or both of which may be provided with teeth or prongs. In most cases, especially where the clasp is intended for use with cords C such as shown in Figs. 2 and 3, only the end of the upper jaw 18 is provided with teeth. In this form of construction the end of the upper jaw 18 is bent downwardly at 21 and the bent portion notched or serrated. For use with double cords such as shown in Fig. 1 the bent end 21 of the jaw is formed with two V-shaped openings, the inclined edges of which are adapted to lie across and bite into the material of the cords C. In some cases, for example to adapt the clasp for use with relatively hard cords such as leather or the like, the lower jaw 19 may be provided with upstanding teeth or prongs 22 sheared from the metal and bent to the form shown in Fig. 11.

The lower jaw 19 of the member 10 is extended in a narrowed lip or ear 23, thereby forming shoulders 24 at its opposite sides for engagement with the detent-fingers 15 on the under flanges 13 of the enclosing member 8 of the clasp. The lip or ear 23 is preferably bent or curved downwardly, as shown in Figs. 2, 3 and 4 to provide a grip for the fingernail whereby the lower jaw 19 may be lifted or sprung upwardly to release the shoulders 24 from the detent-fingers 15 when it is desired to withdraw the inner member 10 from the enclosing member 8. Extending longitudinally of the sides of the lower arm or jaw 19 of the member 10 are flanges 25 formed by portions of the stock bent upwardly at right-angles to the plane of the arm. The flanges 25 serve to maintain the cords C or the strap or band centralized on the lower jaw 19 of the clamping member 10.

The two parts of the clasp are assembled for permanent connection by sliding the inner clamping member 10 within the sides of the enclosing member 8. After the looped end 20 of the slideable member 10 has been entered into the open end of the closing member 8 the ears or lugs 16 are bent inwardly from the sides 12 thereof as shown in Figs. 2 and 6 of the drawing whereby they will be caused to engage through the loop 20 to prevent complete withdrawal of

the member 10. As the member 10 is slid clear into the enclosing member 8 to the position shown in Fig. 4, the two arms 18 and 19 will be compressed or forced together to cause the toothed end of the upper arm 18 to bite into the material of the cords C to clamp the latter securely against the lower jaw. When teeth or prongs 22 are provided on the lower jaw 19, as shown in Fig. 11, these also bite into the material to assist in gripping the cords or band held between the jaws.

As the clamping member 10 slides into the outer enclosing member 8 its lower arm 19 rides across the top of the upwardly projecting detent-fingers 15 to finally seat itself against the underlying flanges 13 with the shoulders 24 at the ends of the jaw engaging behind the fingers as shown most clearly in Fig. 5. With the parts in this relationship the clamping member 10 is locked in closed position with its jaws 18 and 19 maintained clamped against the cords C to securely hold them in place in the clasp.

When it is desired to release the cords, as for example for the purpose of renewing them or for shortening them to adjust the length of the bracelet or the like, then the slideable clamping member 10 may be withdrawn from the enclosing member 8 by pressing against the curved lip or ear 23 to spring the lower jaw 19 upwardly whereby to release its shoulders from the detent-fingers 15 as indicated in Fig. 3 of the drawing. After the detents have been released in this manner the member 10 may be slid outwardly until the loop 20 at its end engages the in-turned lugs 16 on the sides of the member 8 as shown in Fig. 2. The clamping member 10 will thus be held against disconnection from its enclosing member 8 but with its arms 18 and 19 free to spring open as shown in Fig. 2 to release the cords C.

Fig. 8 illustrates a modification in the form of construction of the clamping member or slide 10. In this embodiment of the invention the lower arm or jaw 19 is offset or recessed along its lateral edges at 26 to provide an embossed or crowned central section 27 which seats within the space between the edges of the bottom flanges 13 on the box member 8. This modification in the structure of the inner member 10 provides a smooth, flush finish on the under side of the clasp.

In Fig. 9 a further modified form of construction of the clasp is illustrated wherein both the outer box member 30 and inner slideable clamping member 31 are struck up or embossed to a contour conforming to that of the double cord C, C.

Fig. 10 shows still another modified form of construction of the clasp wherein the outer enclosing member 8 is of tubular form with a closed bottom at 32. With this form of construction the clamping member or slide 10 may be shaped similarly to that previously described, as shown in Fig. 11, being adapted to be completely housed in the member 8 to avoid joints or seams on the under side thereof.

In Fig. 12 the clasp is shown as adapted for use with a leather or fabric strap or band. In this form of construction the enclosing member 8 is of less depth or thickness and the clamping member 10 is also narrowed.

Fig. 13 illustrates a similar form of construction of the clasp having its inner clamping member 10 adapted for gripping the end link of a chain or bracelet. In this embodiment of the

invention the end of the upper jaw 18 of the inner clamping member 10 is formed with a hooked projection 33 which is adapted for insertion through the opening in the link 34 to engage around the end crossbar thereof.

Fig. 14 illustrates the improved clasp as adapted for use with mesh bracelets or bands in which case the upper jaw 19 is provided at its end with serrations forming fine teeth for gripping the metal mesh of the band 35.

Fig. 15 illustrates a modified form of construction of the inner clamping member 36 which is shown as having its upper and lower jaws made separate and pivoted together at one end by means of a hinged joint 37 connected by a pin or pintle 38.

The present improved clasp may be furnished as a fitting or connector for various types of articles embodying looped cords, leather straps, mesh bands and chains or linkages of other types. The two telescoping members of the clasp are assembled in connected relationship in the manner as explained to prevent their separation and loss of either of the parts. With the members assembled and the slide 10 withdrawn from the member 8 the end of the double cord or other strap or band is slipped into place between the two arms or jaws 18 and 19. The two jaws may then be pinched together in the fingers to impinge the toothed end or ends thereof against the material of the cord or band while the member 10 is slid into the enclosing member 8. The act of sliding the member 10 within the member 8 causes the arms to be automatically forced toward each other as shown in Fig. 3 to clamp their ends firmly against the material inserted therebetween and after the slide 10 has reached a position completely enclosed within the member 8 the lower jaw 19 will snap into place with its shoulders 24 engaged with the detent-fingers 15 as shown in Fig. 5 of the drawing. The telescoping action of the parts of the clasp thus has the effect to securely bind the clamping jaws against the cord, strap or other band or linkage to grip and securely hold it in the clasp without danger of accidental release thereof.

After the slide 10 has been assembled in telescopic relationship with the outer member 8 the clamping member is entirely concealed from view so that the raw ends of the cord, strap or other band are hidden and the clasp is entirely devoid of any obtrusive mechanical appearance. That is to say, all the mechanical parts are enclosed and concealed from view within the outer member which may be shaped to ornamental contour as indicated in the drawing and, when desired, embellished with designs or other ornamentation.

Thus the present improved clasp has a very neat and finished appearance besides being very compact in size. Moreover, the complete device is extremely simple in construction as embodying only two elements which may be formed from sheet-metal and assembled without the use of pins, rivets, screws or other extraneous parts.

As a further feature of improvement the improved clasp is proof against damage or breakage to render it durable in use over long periods and it has practically a universal application to various uses in the jewelry and kindred arts.

While the improved clasp is herein shown as embodied in a preferred form of construction with several modifications illustrated, it is to be understood that further changes may be made in the form and arrangement of its parts without departing from the spirit or scope of the

invention. Therefore, without limiting myself in this respect, I claim:

1. In a device of the type indicated, the combination of a hollow member, and a member slideable within the hollow member and provided with opposed jaws adapted to be contracted by the relative sliding movement of said members to grip a cord, strap, band or linkage therebetween, one of said jaws having widely-spaced teeth adapted to straddle a plurality of cords and the other jaw having relatively fine sharp teeth adapted to pierce the cords and bind them between the teeth on the opposite jaw.

2. In a device of the type indicated, the combination of an outer enclosing member, a member slideable within the enclosing member and provided with toothed jaws for gripping the end of a cord, strap, band or linkage, detent means for maintaining said slideable member telescoped within the enclosing member, and projections at the end of the enclosing member bent inwardly from its sides to form stops for preventing the complete withdrawal of the slideable member from within the enclosing member.

3. In a device of the type indicated, the combination of an outer enclosing member, a clamping member formed with a looped end with arms projecting therefrom and provided with means for gripping a cord, strap, band, linkage or the like therebetween, projections on the outer member engaging the loop of the clamping member to prevent the latter from being completely withdrawn from the outer member, and detent-means engageable with one of the arms of said clamping member to maintain the latter enclosed within the outer member.

4. In a device of the type indicated, the combination of a tubular member adapted for attachment to a chain or linkage and formed with lugs at one end projecting inwardly from its sides, and a looped clamping member slideable within the tubular member and held from withdrawal by the lugs at the sides of the latter engaging its loop, said clamping member formed with opposed jaws adapted to grip the end of a cord, strap, band or linkage when said clamping member is telescoped within the tubular member.

5. In a device of the type indicated, the combination of a tubular member having an integral loop at one end for coupling it to a bracelet connector, lugs at its opposite end bent inwardly from its sides, and a looped member slideable within the tubular member and held from withdrawal therefrom by the lugs on the sides thereof engaging its loop, said looped member having jaws at its outer end for gripping a strap, cord or the like.

6. In a device of the type indicated, the combination of a tubular member having means at one end for coupling it to a bracelet connector with its opposite end formed with lugs projecting inwardly from its sides and fingers bent up from its bottom portion, and a loop-like clamping member slideable within the tubular member and provided with jaws at its end for gripping a cord, strap or the like, the loop at one end of said clamping member being engaged by the lugs at the sides of the tubular member to prevent separation of the parts and one jaw of the looped member being adapted to snap in back of the fingers at the bottom of the tubular member to hold the looped member telescoped within the tubular member.
